STARTING DEVICE

Hugo Cordes and Paul Pfeiffer, Hamburg-Altona, Germany

Application January 11, 1938, Serial No. 184,500
In Germany February 2, 1937

5 Claims. (Cl. 123—7)

For those starting impact devices having a stationary cylinder and freely movable ram for pile driving and for similar devices wherein the ram is raised inside the cylinder by the gases produced by the combustion of liquid fuels and for the operation of which fresh air or a gas mixture is used, the downward movement of the ram being accelerated by compressed air present above the latter, a particular starting device has 10 to be used.

In starting devices of this type at present known a disadvantage arises from the fact that the grip device for lifting the ram can be released and the ram can be dropped only if the hammer rests upon the pile. The drop and downward acceleration of the ram consequently begin only after the hammer rests upon the pile, so that only the ramming and falling height provided within the cylinder will be available for 20 starting purposes. When cold the oil in the cylinder is very viscous and often dirtied by impurities from the exhaust gases. Besides, a vacuum results above the ram during its dropping, which vacuum cannot be completely overcome by the air inlet valve, it being not possible for practical reasons to make such valve of adequate size, to entirely prevent the formation of a partial vacuum. In cold weather the falling height available for starting under these conditions will not suffice, it is therefore desirable to raise the lifted ram together with the cylinder from the pile and to simultaneously drop both parts. At the time of the cylinder's meeting the pile the ram will have such a falling speed that 30 in connection with the falling speed given the ram when falling within the cylinder, it will suffice for starting. For this purpose a grip device is required which reliably releases the ram when the cylinder has met the pile.

40 In Figs. 1-14 some embodiments of the invention are schematically represented by way of example.

Fig. 1 is a view of one form of the starting device in longitudinal section, the longitudinally movable tie-rod with the grip-hook being held from rotation;

Fig. 2 shows a second form of the device with the grip-hook engaged;

Fig. 3 is a view of the device shown in Fig. 2 but with the grip device lowered and the coupling bar disengaged;

Fig. 4 is a view, partly in section, and partly in elevation of a third form of grip-device and a ram and cylinder, the ram being in its lowermost position;

Fig. 5 is a vertical section at right angles to Fig. 4, with the ram lifted by the grip device to its uppermost position in the cylinder;

Fig. 6 shows in detail the upper part of the cylinder of Fig. 5 and the grip device on an enlarged scale;

Fig. 7 is a view similar to Fig. 6, the grip device being released;

Fig. 8 is an edge view of a special form of a chain used in this third form;

Fig. 8a is a face view of this chain;

Fig. 9 is an enlarged detail of the upper part of Fig. 4;

Fig. 10 is a section on the line X—X of Fig. 9;

Fig. 11 is a detail of the latching means on a greatly enlarged scale;

Fig. 12 is a front view of a certain cage used in the third form;

Fig. 13 is a side view of this cage; and

Fig. 14 is a plan view of this cage.

In the form shown in Fig. 1 there is disclosed a cylinder casing 1 through the top of which a tie-rod 2 is arranged to slide vertically. To the said tie-rod a grip-hook 10 is pivotally fixed, being urged to its engaged position by a spring 11. In the cylinder casing 1 is journaled a shaft 7 on which is fixed a hook 3. Also the shaft 7 has fixed thereto a lever 8 to which is attached a rope 14. The hook 3 is held in engaged position beneath an arm 10a of the hook 10 by a spring 4. The cylinder casing 1 may rest upon a support, for instance, a pile. Inside the said casing is a vertically movable ram 13. When dropping down, the said ram strikes the said support. The ram 13 is provided with a recess 13a having a peripheral groove 33 in which the grip-hook 10 may engage. A key 15 engages a splineway 15a so that the tie-rod 2 is prevented from rotating. The lifting rope 16 is fixed to the tie-rod 2.

In the embodiment according to Figs. 2 and 3, the grip-hook 10b is pivoted to the lower end of a movable sleeve 5. Vertically above the point where the grip-hook 10b engages the ram 13c, the grip-hook rests with the face of its hooked portion on the tie-rod 2a. The upward movement of the said sleeve 5 is limited by a collar 18 fixed on a tie-rod 2a. By means of a plunger or dog 3a urged to engage a groove 2c on the sleeve 5 by a spring 4a the said sleeve 5 may be latched to the cylinder casing 1a. A shaft 7a is mounted on the cylinder 1a and has levers 6a and 8a fixed thereto, the lever 6a engaging the dog 3a and the lever 8a being connected to a rope 14a.

The dog 3a can be disengaged by means of levers 6a and 8a upon drawing on the rope 14a. If the ram is elevated in the cylinder and ram are dropped on a pile which allows the hoisting rope 16 to go slack, the tie-rod continues to descend due to its own weight until the collar 18 comes to rest on the sleeve 5 which is held by dog 3a. The various parts are now in the position shown in Fig. 3 except for the fact that the sleeve is latched to the top of the cylinder. The latch 12 acts on the hook 10b during this further descent of the tie-rod 2a and disengages the hook 10b from the ram 13c. However, the latch 12 only maintains the hook 10b in its disengaged position when the hoisting rope 16 is slack and the sleeve 5 is held at the top of the cylinder by the dog 3a.

The upper portion 10d of the hook member 10b functions in the following manner. When the member 2a is depressed, the member 12 tilts the hook to free it from engagement with the member 13c, but when the member 2a is raised after the latch has been depressed by contact with the ram 13c, the portion 10d is engaged by the portion 2e and is biased to engage with the member 13c.

In the forms shown in Figs. 2-3 the ram is provided with a bore 39 for guided reception of the lower end 2e of the member 2a.

The method of operating the first form is as follows:

For starting operation a lifting rope 16 is connected to the top part of tie-rod 2. After this the shaft 7, by drawing the rope 14 downwardly is rotated to such an extent that the hook 3 is disengaged. Upon loosening the lifting cable the tie-rod 2 with the parts attached to it will drop down on account of its dead weight. The grip-hook 10 will latch with ram 13. By means of lifting rope 16 the rod 2 is now lifted together with ram 13. In the uppermost position of the tie rod with respect to the casing 1 the hook 3 is automatically engaged with arm 10a thus holding in engaged position the hook 3. This prevents the tie-rod from reentering the cylinder beyond a certain point, the reentering action being the means used to trip the hook free of the ram. Upon further upward action of the lifting cable the whole hammer is lifted, while hook 10 continues to engage the ram. The automatic releasing of the ram 13 is effected by sudden loosening of the lifting rope 16 after the ram has come to rest on the pile head. By this means the tie-rod 2 is moved a little downward in the casing 55 thus causing hook 10 to be released.

In the embodiment of Fig. 1 the grip-hook 10 is already shown in its disengaged position. Rod 2 has already dropped down on account of loosening the lifting cable. During this operation the contact face between parts 10 and 3 has been the centre of rotation about which hook 10 has rotated.

For starting the second modification, shown in Figs. 2 and 3, the sleeve 5 is disengaged from the top portion of the cylinder by pulling the rope 14a, thereby unlatching the dog 3a against the action of spring 4a. Upon loosening the hoisting cable 16 the tie-rod 2a together with sleeve 5 travels down. When latch 12 strikes the ram 13c (as shown in Fig. 3), the spring 11a is compressed by the weight of the tie-rod. Then the weight of sleeve 5 turns hook 10b about face 10d of its hooked portion, thereby engaging hook 10b with the ram. For guiding the tie-rod 2a when the hoisting cable enters the cylinder the ram 13c is

provided with a bore 39. The ram is then hoisted within the cylinder, and upon further upward movement of the rope the whole hammer is lifted. In the uppermost position of the ram with respect to the cylinder 1a, sleeve 5 is secured to cylinder 1a by the dog 3a. When, after loosening the hoisting rope, the hammer comes to rest on the pile, the tie-rod can travel further down until shoulder 18 rests on sleeve 5. While the tie-rod is travelling further down, the face 10d of the hook no longer finds a support on the tie-rod. Hook 10b turns about bolt 19 in sleeve 5 accordingly, and the ram is unlatched from the hook.

By means of the latch 12 the grip-hook may be held in its disengaged position, so that it will not be able to grip the ram 13c while the latter is in operation, even if the lifting cable 16 is raised again until the member 2a has been fully raised.

The grip gear according to Figs. 4-14 for the ram comprises a cage 20 with tapered levers 10c, as shown on an enlarged scale in Figs. 11 and 13. Furthermore a wedge rod 21 is inserted from above into the slot 22 of the cage 20, and the tapered levers 10c are pivoted within cage 20 by bolts 23. If the tapered levers 10c are to be released, the wedge rod 21 is lowered down to the face 24 of cage 20. The wedge rod 21 is secured to a drum 25 by means of a chain 31. Releasing levers 26 pivotally mounted on shaft 35 cooperate with the said wedge rod 21 and drum 25 in such a way that levers 26 support the cage 20 by means of lugs 28 on the cage 20.

If cage 20 is suspended from the wedge rod 21, the tapered levers 10c engage at their lower ends against the faces 29 on the lower end of the rod and against faces 30 on the upper end of wedge rod 21.

The three views, Figs. 12, 13 and 14, showing the cage 20 clearly disclose the suspension lugs 28, which rest on the faces 31 of releasing lever 26.

Fig. 11 shows an annular inclined shoulder 32, formed in the bore 33a of ram 13d and has a steeper angle than face 29 of the wedge rod 21.

As in Fig. 10 the releasing levers 26 are provided with an engaging spring 34 (see also Fig. 6). The levers 26 are fixed on the shaft 35 and the disengaging lever 8b for the cable 14b is also fixed on shaft 35. 36 designates a screwed in bolt 50 securing the tie chain 37 to the drum 25.

For permitting a proper co-operation of members 10c with 32, for guiding cage 20, a pipe-shaped elongation 38 is slidably arranged within a corresponding recess 39 of ram 13d.

The grip device according to the present invention is latched to ram 13d by spreading the tapered levers 10c when the wedge rod 21 is raised by tightening the chain 31, the tapered levers 10c bearing against the tapered shoulder 32 within ram 13d. If the ram 13d has been lifted to its uppermost position, the releasing levers 26 with the surfaces 31 will slide under the lugs 28. When the drum 25 is rotated rearwardly so that the chain 31 is unwound, the lugs 28 of cage 20 will engage the surfaces 31 of the releasing levers 26, the latter being retained by spring 34. Upon further downward movement, cage 20 with the tapered levers 10c is latched, while the wedge rod 21 continues to drop, thus permitting the tapered levers 10c to unlatch from the ram so that it may drop freely. Upon further rotation of drum 25, the faces 40 of drum 25 engage faces 31, Figs. 6 and 7, and are locked by releasing lever 26, so that during the operation of

ram 13d the whole lifting and releasing mechanism, comprising parts 20, 10c, 21, and 38 is supported by the drum. The wedge rod 21 is maintained in its lowered position and the tapered levers 10c remain unlatched in order that the ram 13d cannot be latched by the tapered levers 10c even in its uppermost position.

Upon dropping the whole pile driving hammer with its ram lifted, the speed of ram 13d and of cylinder 1b will be the same when meeting the pile. The cylinder 1b will be suddenly stopped, while the tie member (chain) 31 and the wedge rod 21 continue to move so that the tapered levers 10c are released, without producing any pressure of importance, by the action of the weight of the ram on the inclined surfaces of the tapered levers, the wedge rod 21 and ram 13d.

Upon lifting the grip device, the releasing levers 26 automatically give way. For releasing the grip gear, the cable 14b is tensioned, releasing levers 26 by means of lever 8b and shaft 35 compressing the engaging spring 34.

Diesel hammers of the larger sizes are difficult to lift by a single rope and are preferably lifted by means of a cable passing around a loose pulley, such hammers having their height increased by the construction height of the loose pulley (Fig. 5). For reducing this extra construction height, a drum 25 is arranged inside the cylinder 1b, the said drum having a shaft 41 projecting laterally from the cylinder.

Toothed wheels 42 are mounted on both shaft ends and are engaged by racks 43. The tops of said racks are connected by a yoke 44 on which the loose pulley 45 is mounted. The diameter of drum 25 in proportion of the diameter of the toothed wheels can be increased according to the proportion of the weight of ram 13d to that of cylinder 1b. The weight of cylinder 1b should, however, be considerably greater than that of ram 13d, not only for structural reasons but also in view of the fact that it will have to resist lift due to the retarding air pressure above ram 13d. It thus will be possible to lift the ram by means of racks having a considerably lower lift than the ram.

The chain wheel 25 and chain 37 with the rack 43 and the parts carried by it are shown only by way of example as a particular embodiment for a special purpose of application of the invention, i. e. if the loose pulley 45 is to be used (see Figs. 4 and 5). However, in the place of such an auxiliary means a direct transmission 55 may be used. The chain 37 can be connected directly with the lifting cable or any connection known in itself can be made with the said cable, it being understood that the locking parts 40 and 28 are made of corresponding shape.

If for any reasons the lifted ram 13d should not be released, the releasing lever 26 may be prevented from engaging by pulling on cable 14b, or when engaged the said lever can be released in the same way.

For reducing as much as possible the diameter of the chain drum in the cylinder cover, the tie member 31 is a link chain, one half comprising a single strand and the other half comprising two chain strands, arranged to permit 1 1/4 windings on the drum. For the same purpose a chain 37a according to Figs. 8 and 8a could be used, the links of which are riveted together in staggered form and are wound on the drum in spiral shape.

What we claim is:

1. In a device for the purpose set forth and having a cylinder, lifting means therefor and a ram slidable in said cylinder and provided with a circumferentially grooved recess in its upper end; latch means for releasably holding the ram elevated in said cylinder including a pivoted latch member movable into and out of the ram recess to engage in said groove, means for urging the latch member in engagement in said groove, vertically movable means in the upper part of the cylinder having operative connection with the cylinder lifting means, and means controlled by downward movement of said vertically movable means for releasing the latch from the groove and thereby freeing the ram.

2. In a device for the purpose set forth and having a cylinder, lifting means therefor and a ram slidable in said cylinder and provided with a circumferentially grooved recess in its upper end; latch means for releasably holding the ram elevated in said cylinder including a pivoted latch member movable into and out of the ram recess to engage in said groove, means for urging the latch member in engagement in said groove, a tie rod slidable through the upper end of the cylinder, and means controlled by downward movement of said tie rod for releasing the latch member from the groove and thereby freeing the ram.

3. In a device for the purpose set forth and having a cylinder, lifting means therefor and a ram slidable in said cylinder and provided with a circumferentially grooved recess in its upper end; latch means for releasably holding the ram elevated in said cylinder including a pivoted latch member movable into and out of the ram recess to engage in said groove, means for urging the latch member in engagement in said groove, a tie rod slidable through the upper end of the cylinder, means controlled by downward movement of said tie rod for releasing the latch member from the groove and thereby freeing the ram, and manually releasable means for preventing downward movement of the tie rod beyond a certain point.

4. In a device for the purpose set forth and having a cylinder, lifting means therefor and a ram slidable in said cylinder and provided with a circumferentially grooved recess in its upper end; latch means for releasably holding the ram elevated in said cylinder including a pivoted latch member movable into and out of the ram recess to engage in said groove, means for urging the latch member in engagement in said groove, a tie rod slidable through the upper end of the cylinder, means controlled by downward movement of said tie rod for releasing the latch member from the groove and thereby freeing the ram, a second latch member carried by the cylinder and preventing downward movement of the tie rod beyond a certain point when in one position, spring means urging said second latch member into said position, and manually operable means for moving the second latch member against the action of the spring whereby to free the tie rod.

5. The device of claim 3, characterized by having the means for preventing said downward movement of the tie rod engaging the latch member.

HUGO CORDES.
PAUL PFEIFFER.
